DINNER PLATE OR SIMILAR ARTICLE

William C. Richardson, Los Angeles, Calif., assignor to Technical Porcelain and Chinaware Co., El Cerrito, Calif., a partnership

Application July 8, 1950, Serial No. 11,009

Term of patent 14 years

(Cl. D44—15)

To all whom it may concern:

Be it known that I, William C. Richardson, a citizen of the United States of America, residing in the city of Los Angeles and county of Los Angeles and State of California, have invented a new, original, and ornamental Design for a Dinner Plate or Similar Article, of which the following is a specification, reference being had to the accompanying drawing, forming part thereof.

The figure of the drawing is a top plan view of a plate having a conventional configuration embodying my new design; a repeat unit of which is shown in full lines. The said unit being repeated about the remainder of the circumference shown in dotted lines.

I claim:

The ornamental design for a dinner plate or similar article, substantially as shown and described.

WILLIAM C. RICHARDSON.
